[57] ABSTRACT

A distillation system comprising: a vaporizing kettle; an auxiliary pressurizing boiler connected at its input to the output of the kettle; a condenser heat exchanger connected at its input to the output of the boiler and having a plurality of spaced taps from which distillate can be removed; supplementary cooling tower in circulating flow relationship with the exchanger; a like plurality of distillate storage vessels; and means connecting each tap to the input of the corresponding vessel.

DISTILLATION MECHANISM AND SYSTEM

SUMMARY OF THE INVENTION

I have invented a new and highly improved distillation mechanism and system to obtain separation and purification of liquids. It is specifically intended for reclaiming polluting chemicals while simultaneously producing pure water and/or other liquid carriers.

Unique devices and features accomplish this most reliable method known with unequaled economy. Heats of the boiling vapors are absorbed in the condenser unit by the incoming raw substances to be boiled just prior to entry into the boiling kettle. This causes the liquid being processed to be at almost boiling temperatures when heat is applied only for this purpose.

The mechanism is constructed of existing materials, properly selected to resist all chemicals and proposed temperatures, using low cost control equipment and materials that compare favorably with conventional like mechanisms. Methods of manufacturing are of common practice and the mechanism has an inherently long operating life.

All requirements for properly distilling liquids are complied with. Included are the best of existing practice plus unique techniques of equalizing heat necessities by useful exchange in condenser and kettle, vapor phase separation, the use of added internal cooling surface for condensing, an auxiliary boiler like decomposer of azeotropic solutions, and a naturally operating pressure relief valve. All are combined into one most effectively and simple operating mechanism.

My invention compares favorably to prior systems but has the following specific advantages:

1. Cost for operating energy is reduced by more than five fold.
2. Raw liquids of any type or mixes thereof may be processed.
3. Solids and semi-solids are recovered as a high concentrated residue.
4. Processing time is reduced as are heating requirements.
5. Only inert gas escapes to the atmosphere (and may be simply trapped).
6. Either single batch or continuous operation is available.
7. Multiple operations normally performed for separation and purifying of most aqueous and azeotropic solutions require only one of the two possible operation methods provided.
8. Waste chemicals are, in most instances, readied for reuse on recovery.

A few of the more important uses for this distillatory system which result from the above advantages are:

1. To control future water resources and to rid water resources of contamination while recovering the chemicals and water involved.
2. Refining of organic substances as oils, petroleum, waxes, etc.
3. To provide drinking water from seas, sewages or other like sources.
4. To conserve and possibly restore natural chemical, mineral, water, and wild-life resources. In any application the recovered substance or substances are much more valuable than the cost of equipment and operation involved.

5. Antipollution becomes an asset in place of costly liabilities for industry or individual users.

BRIEF DESCRIPTION OF THE DRAWINGS

- 5 In the drawings:
- FIG. 1 is a view of the system in accordance with my invention;
- FIG. 2 is a view taken along line 2—2 in FIG. 1,
- FIG. 3 is a view taken along line 3—3 of FIG. 1, and
- FIG. 4 is an enlarged view of a portion of the structure of FIG. 1.

DETAILED DESCRIPTION OF PREFERRED EMBODIMENTS

15 In the drawings, the following parts have the following numbers:

- 10 vaporizing kettle
 12 condenser-heat exchanger
 14 residue outlet
 16 vapor phase separator
 18 thermostatically controlled heater
 20 inner dome and shell
 22 inlet flow valve, level controlled
 24 uncondensable trap-ventilator
 26 raw liquid diffuser
 28 uncondensable vapor passage
 30 return line
 32 coolant feed pump
 34 coolant feed valve
 36 inner supplementary cooler
 37 bulbed vapor enclosure
 38 drain line and condenser support
 39 bulb flow spreader
 40 drain control valve
 42 pressure relief valve
 44 storage drain off valve (can be used for delivering heated condensate water to steam generators)
 46 distillate stowage
 48 supplementary cooling tower
 50 feed line and pump
 52 raw liquid intake or feedline
 54 auxiliary boiler, pressurizing
 56 chiller gas coil
 58 chiller gas expansion tank
 60 chiller gas compressor
 62 inner coolant chiller
 63 progressive chambers
 64 heaters
 66 check valves
 68 inlet valve to auxiliary boiler
 69 outlet flow valve to kettle
 70 tubular ring
 72 inner shell
 74 inner dome
 76 lateral hole
 80 raw liquid diffuser
 82 raw liquid cooling area
 84 internal cooling area
 86 vapor condensing area
 88 kettle feed outlet
 90 distillate outlet

FIGS. 1—4 exhibit the arrangement of devices and the mechanism which all function in the following manner.

The kettle 10 boils or vaporizes the liquid most efficiently by heating centrally. The inner dome and shell 20 flows the liquid down the outer perimeters to insulate or keep heats inside by absorbing and returning

such back into the main heating area. To obtain automatic and more proper liquid level control, an electrical conductivity cell **T** is used to operate the inlet flow valve **22**. A manually controlled residue outlet valve **14** permits the extent of distillation reduction desired and depends on raw liquid characteristics. An electrical heater **18** is shown and utilized due that close heat control is provided and no air pollution problems created. (If other type heaters are desirable they may be used optionally.) The volatile fractions, dependent upon raw liquid character and the heater temperature selected setting, escape the kettle through a spout affixed with a sieve like device **16** that initiates vapor molecule separation, effecting purity of condensation immediately following. (This device was introduced since radiant energy can be so divided and diffracted into desired spectra by similar grating.)

The condenser **12** liquefies heated vapors produced by the kettle **10** and additionally serves as a heat exchanger. Ordinary condenser systems only cool the vapors and the coolant is discharged (wasted) hot or re-cooled. This condenser utilizes the raw liquid to be distilled as the coolant and discharges it into the distillation kettle. The unit is slanted to allow lighter vapors to float slowly upward where cooling is greater and also to permit complete emptying. Escaping vapors are conducted through the condenser between two cooling or heat exchange surfaces or bulbed tubular enclosures **37** being matched as shown. The outer surfaces exchange most of the vapor heats, with the cooler raw substances being flowed into the kettle. The inner surface, operating somewhat colder, promotes complete condensation of the vapor fraction involved at the bulb by continually seeding the appropriate liquid causing capillary attraction. As in ordinary systems higher boiling point fractions of liquids condense first nearer the kettle which occurs immediately when the vapors are reduced to the initial boiling point of the respective liquid minus 1° Fahrenheit (latent heat).

The mating bulbs form a trap and enlarged cooling surface for the appropriate vapor fraction to condense into liquid that is recovered. A small uncondensable vapor pass **28** connects the larger vapor enclosure bulbs **37** to prevent trapping of such gases therein that would create useless space and surfaces. The inner bulb **36** is a supplementary cooling surface that utilizes minimal yet adequate fluid flowing along its outer surface as accomplished by inserting the bulb flow spreader **39**. The raw liquid feed equally distributes the incoming raw substance sufficiently over the larger condenser bulbs **37** for more effective cooling and extraction of closer and narrow boiling point liquid fractions. Uncondensable gases or vapors are naturally forced through a trap **24** of appropriate absorbent media just before venting. (Commercially available activated carbon, ion-exchange resins, silica-gel, or zeolite will serve the media purpose of removing all active or harmful gaseous chemicals.) The outlet vent is tubular and pointed downward to protect from weather and to permit easy attachment of vacuum that is necessary to prevent cracking of low molecular weight hydrocarbons by heats of boiling, and the separation of most aqueous and azeotropic solutions at lower than boiling point temperatures under 1 atmosphere pressure. Vacuum will also speed distillation rates of all liquids but the energy cost would be greater than that for operating this mechanism. Also the disease causing bacteria will not

be killed under vacuum heats, when drinking or potable water is desired.

Storage of distillate, (condensed vapors of boiling fractions), include the drain lines **38** from the condenser which also support that unit. Drain valves **40** control the flow and are opened only when the lines are filled. These may be either automatically or manually operated. A pressure release valve **42** of conventional type and on the drawings on each storage tank **46** provides for safety therein. Its weight closes the device after it is opened by excessive inside pressures, and the cover rim protects from exterior contamination when open at low pressure. This device is also unique in its simplicity in providing positive operation without dependence on added highly critical, yet integral, parts. The storage release valve **44** is common for manually emptying storage vessels.

Raw liquid feed **52** necessitates a pump **50** for transfer of substances to the distillation mechanism as convenient for the user. For peak operation it should be adjusted at some 10 pounds per square inch pressure in normal (relatively small) operations. The raw liquid feed distribution inside the condenser was discussed above except that a perforated pipe will serve the purpose.

The cooling system and coolant for the inner bulb of this distillary mechanism use conventional devices, equipment, materials. These consist of a cooling tower **48**, chilling container with coil **56**, a gaseous refrigerant, compressor **60** and expansion chamber **58**.

The auxillary boiler **54** is intended for thermally separating the very few azeotropic, constant boiling point mixtures (CBM) solutions only if the separation cannot be done with reduced pressure (vacuum). This is accomplished by progressive heating in cylindrical chambers **63** separated by heating elements **64** and the chambers being connected with one way check valves **66**. This permits heating and pressure control of liquid and vapor constituents as individually applicable, especially where multiple substances make up the azeotrope. Such a progressive heating system is more advantageous since thermal separation of otherwise unseparable components of vapor phases are exposed to that individual necessary heat without dependence of extremely high pressure as normally acquired and required in conventional mechanisms and methods, unless prior separation has been performed. The release pressures for the valves may be predetermined and installed as fixed releases for applicable solutions or adjustable release pressure to permit various type solution processing. This type boiler is also advantageously applicable to produce steam for generating electricity to power the mechanism if the need arises. To produce steam pure water, obtained as herein disclosed, is necessary.

The materials of construction for the mechanism should withstand all chemicals and environments to 1000°F which is adequate for superheated steam heat generation.

While I have described my invention with particular reference to the drawings, such is not to be considered as limiting its actual scope.

Having thus described this invention, what is claimed and asserted as new is:

1. A distillation system comprising:

a condenser-heat exchanger with separate first, second and third flow paths directed therethrough, the

first flow path being traversed by liquid which is to be distilled, the second flow path being traversed by heated vapors which are to be condensed and the third flow path being traversed by a recycled coolant, the paths being concentric in the order named so directed that the vapors in the second flow path lose their heat both to the liquid which is to be distilled and to the recycled coolant; means for recycling the coolant and removing heat that is transferred thereto; a vaporizing kettle receiving liquid that has traversed the first flow path and has been heated therealong, the kettle vaporizing the liquid and directing it into the second flow path; a plurality of tanks communicating with the second flow path along axially displaced points thereon to

receive distillate condensed therein; and a bypassable auxiliary boiler disposed between the condenser and kettle in the first flow path, the boiler having a plurality of chambers connected in series with one way check valves connected between successive chambers, and further having a like plurality of heaters, each heater heating a corresponding chamber.

2. The device of claim 1 wherein the vaporizing kettle incorporates a heater, and wherein the heater in the kettle is of the electrical type.

3. The device of claim 2 wherein an electrolytic cell disposed in the kettle cooperates with a valve disposed between the auxiliary boiler and the kettle along the first flow path to control the level of liquid in the kettle.
